UNITED STATES PATENT OFFICE.

LAWRENCE P. FLESHNER, OF KANSAS CITY, MISSOURI, ASSIGNOR OF ONE-HALF TO
WILLIAM L. HOTSENPILLER, OF KANSAS CITY, MISSOURI.

NURSING-BOTTLE HOLDER.

Application filed May 6, 1926. Serial No. 107,117.

My invention relates to improvements in nursing bottle holders.

One of the objects of my invention is to provide a novel structure that may be set upon the floor, a bed or other suitable surface, which can be adjusted as to width to suit the place which it is to occupy, which provides novel means for supporting a nursing bottle in a position convenient for a baby 10 to nurse therefrom, and which may serve as a canopy for supporting mosquito netting.

A further object of my invention is to provide a nursing bottle holder of the kind described, which is simple, cheap to make, 15 which is light, durable, strong, not liable to get out of order, which is easily operable, and which will afford entertainment for the infant with which it is employed.

The novel features of my invention are 20 hereinafter fully described and claimed.

In the accompanying drawing, which illustrates the preferred embodiment of my invention,

Fig. 1 is a perspective view of my improved nursing bottle holder shown supporting a bottle and a portion of a mosquito netting mounted thereon.

Fig. 2 is an enlarged cross sectional view showing the chain belt and parts connected therewith, parts being broken away.

Fig. 3 is an enlarged section on the line 3—3 of Fig. 1.

Fig. 4 is a plan view of one of the rubber band engaging links.

Similar reference characters designate 35 similar parts in the different views.

The holder is provided with supporting means comprising, preferably, two arched crossed supporting members, which may be 40 flat arched bars 1 and 2 pivoted together on a vertical axis by a rivet 3 having at its lower end an eye 4.

The bars 1 and 2 are adapted to be swung 45 toward and from each other on the rivet 3 to vary the width of the space occupied by the holder.

To fasten the bars 1 and 2 releasably in 50 the positions to which they may be relatively adjusted, there is provided a flat ring 5, concentric with the rivet 3 and rigidly fastened to the bar 1 at diametrically opposite points by two rivets 6 and 7 provided at their lower ends respectively with eyes 8 and 9.

The ring 5 is provided at diametrically

opposite places with arcuate longitudinal slots 10 and 11. Through the slot 10 extends a thumb screw 12, which bears on a washer 12' resting on the upper side of the ring 5, the screw at its lower end being rotatably fitted in a threaded hole provided in the bar 2.

Rigidly secured to the bar 2 is a rivet 13 which extends through and is movable in the slot 11 lengthwise thereof, and having its upper end rigidly fastened to a washer 14 adapted to have sliding engagement with the upper side of the ring 5. The lower end of the rivet 13 is provided with an eye 15.

16 designates an ordinary nursing bottle having at one end the usual nipple 17. For supporting the bottle in the inclined position with the nipple end down, as shown in Fig. 1, there are provided two bottle supporting devices, each of which comprises the following described parts.

18 designates an arcuate plate adapted to rest on the upper side of the bottle 16 and having centrally secured to it, and extending above it, an eye 19.

One end of the plate 18 is provided with a hook 20, and the other end with an eye 21. Two links 22, one of which is shown in Fig. 4, are respectively mounted in the eye 21 and hook 20, the latter being detachable from the adjacent link 22. Each of the links 22 is provided with a space 23 between its ends through which may be slipped a rubber band 24. The latter is of such a length that it is stretched when mounted on the bottle 16. To remove the bottle, the hook 20 is freed from the adjacent link 22.

The two devices, which are alike in construction, and one of which has just been described, are mounted on the bottle 16 respectively adjacent to the ends thereof. For supporting the rear or upper one of said devices, its eye 19 is releasably engaged by an ordinary snap hook 25, which is fastened to 95 and is supported by a chain 26, which extends through and is supported by the eye 4, Fig. 1.

For supporting the lower or front one of said devices, its eye 19 is releasably engaged by a snap hook 27, Fig. 2, having at its upper end an eye 28, which is mounted and is adapted for traveling on a chain 29, which extends through and is adapted for traveling engagement with the eyes 8 and 15. One 100 105 110

end of the chain 29 is provided with a snap hook 30 adapted to releasably engage different links of the chain 29, so as to form an endless belt that may be adjusted as to 5 length, to raise or lower the nipple end of the bottle 16.

The nipple end of the bottle may also be raised or lowered, by loosening the thumb screw 12 and swinging the bars 1 and 2 on 10 the rivet 3 toward or from each other.

A mosquito netting 31 may be spread over the bars 1 and 2 and ring 5, to form a canopy for covering and protecting the infant from flies or mosquitoes.

If desired, the chain 29 may be made to engage the eye 9, Fig. 1, instead of the eye 8.

In the use of the holder, the rubber bands 24 are made to embrace the bottle 16 and to respectively engage the hooks 20 of the two 20 plates 18, which are mounted on the bottle.

The thumb screw 12 is then loosened, and the bars 1 and 2 are swung to the desired distance apart, after which the thumb screw is tightened. If need be, the nipple end of 25 the bottle 16 is then raised or lowered to the desired position, by releasing the snap hook 30 and making it engage with a link of the chain 29, which will provide the proper length of the chain belt for supporting the 30 bottle at the desired inclination.

I do not limit my invention to the structure shown and described, as modifications, within the scope of the appended claims, 35 may be made without departing from the spirit of my invention.

What I claim is:—

1. In a nursing bottle holder, supporting means including two members pivoted together on a vertical axis and adjustable toward and from each other, two devices having means adapted to engage a bottle respectively adjacent to its ends for supporting the bottle, means supporting one of said devices supported by said members at the axis thereof, a flexible member supported by said members at points spaced from said axis, and fastening means supporting the other of said devices and supported by and having traveling engagement with said flexible member.

2. In a nursing bottle holder, two supporting members pivoted together on a vertical axis and adapted to have their ends supported on a suitable surface, said members being 55 adjustable circumferentially on said axis, a ring fastened concentrically with said axis to one of said members, releasable means for fastening said ring to the other member, and bottle supporting means supported by said two members.

3. In a nursing bottle holder, two supporting members pivoted together on a vertical axis and adapted to have their ends supported on a suitable surface, said members being 60 adjustable circumferentially on said axis, a

ring fastened concentrically with said axis to one of said members, releasable means for fastening said ring to the other member, two devices having means adapted to engage and support a bottle respectively adjacent to 70 its ends, means supporting one of said devices supported by said members at said axis, and means supporting the other device and supported by said two members at points spaced from said axis.

4. In a nursing bottle holder, two supporting members pivoted together on a vertical axis and adapted to have their ends supported on a suitable surface, said members being circumferentially adjustable on said 80 axis, a ring fastened concentrically with said axis to one of said members, releasable means for fastening said ring to the other member, two devices having means adapted to engage and support a bottle respectively adjacent to 85 its ends, means supporting one of said devices supported by said members at said axis, a flexible member supported by said members at points spaced from said axis, and fastening means supporting the other device and supported by and having traveling engagement with said flexible members.

5. In a nursing bottle holder, two arched crossed supporting members fastened together and adapted to have their ends supported on a suitable surface, two devices having means adapted to engage and support a bottle respectively adjacent to its ends means supporting one of said devices supported by said members where they cross each other, a 100 flexible member having means for releasably fastening its end portions together to form an endless belt, and fastening means supporting the other device and supported by and having traveling engagement with said 105 belt.

6. In a nursing bottle holder, two arched crossed supporting members fastened together and adapted to have their ends supported on a suitable surface, two devices 110 having means adapted to engage and support a bottle respectively adjacent to its ends, means supporting one of said devices supported by said members where they cross each other, a chain supported by said two 115 members at points spaced from their crossing point and provided at one end with a hook adapted to engage different links of the chain to form an endless belt adjustable as to length, and fastening means supporting the other device and having traveling engagement with and supported by said chain belt.

7. In a nursing bottle holder, two arched crossed supporting members pivoted together on a vertical axis so as to be circumferentially adjusted toward and from each other, releasable means for fastening said members in the positions to which they may be adjusted, two devices having means adapt- 125

ed to engage and support a bottle respectively adjacent to its ends, means supporting one of said devices supported by said two members at said axis, a chain supported by 5 and having traveling engagement with said two members at points spaced from said axis, said chain at one end having a hook adapted to engage different links of the

chain to form an endless belt adjustable as to length, and fastening means supporting 10 the other device and supported by and having traveling engagement with said belt.

In testimony whereof I have signed my name to this specification.

LAWRENCE P. FLESHNER.
